CLAIM

We claim the ornamental design for a cartridge cover, as shown and described.

DESCRIPTION

FIG. 1 is a perspective view of a cartridge cover showing our new design;

FIG. 2 is a top plan view of the design of FIG. 1;

FIG. 3 is a bottom plan view of the design of FIG. 1;

FIG. 4 is a left side elevational view of the design of FIG. 1;

FIG. 5 is a right side elevational view of the design of FIG. 1;

FIG. 6 is a front elevational view of the design of FIG. 1;

FIG. 7 is a rear elevational view of the design of FIG. 1;

FIG. 8 is a cross-sectional view taken along line 8-8 in FIG. 2;

FIG. 9 is a perspective view of an alternate embodiment of the design shown in FIG. 1;

FIG. 10 is a top plan view of the design of FIG. 9;

FIG. 11 is a bottom plan view of the design of FIG. 9;

FIG. 12 is a left side elevational view of the design of FIG. 9;

FIG. 13 is a right side elevational view of the design of FIG. 9;

FIG. 14 is a front elevational view of the design of FIG. 9;

FIG. 15 is a rear elevational view of the design of FIG. 9; and,

FIG. 16 is a cross-sectional view taken along line 16-16 in FIG. 10.

The broken lines shown in the drawings illustrate portions of the cartridge cover that form no part of the claimed design.
